UNITED STATES PATENT OFFICE.

EARLE R. NEWTON, OF NEW YORK, N. Y., ASSIGNOR TO INTERNATIONAL CURTIS
MARINE TURBINE COMPANY, OF NEW YORK, N. Y., A CORPORATION OF WEST
VIRGINIA.

ELASTIC-FLUID TURBINE.

1,268,272.

Specification of Letters Patent. Patented June 4, 1918.

Application filed March 9, 1917. Serial No. 153,593.

To all whom it may concern:

Be it known that I, EARLE R. NEWTON, a citizen of the United States, residing in the city, county, and State of New York, have 5 invented a certain new and useful Elastic-Fluid Turbine, of which the following is a specification.

My invention relates to improvements in elastic fluid turbines and has particular reference to such turbines used for the propulsion of ships.

The objects I have in view are to so construct and arrange an elastic fluid turbine as to obtain a high efficiency at both reduced 15 power and high power and to secure a desired division of power between certain parts of the turbine.

These and further objects will more fully appear from the following specification and 20 accompanying drawings considered together or separately.

Figure 1 of the accompanying drawings illustrates a turbine design and arrangement embodying my invention.

Fig. 2 illustrates a modification in which the turbine embodying my invention is arranged to operate as an additional or cruising turbine, and

Fig. 3 illustrates a further modification in 30 which the low pressure elements of the turbine is divided into two groups and geared to the propeller shaft.

In all views, like parts are designated by the same reference characters.

According to the present invention I secure high efficiency at reduced power and reduced revolutions by arranging a sufficient 35 number of stages or rows of blades to operate in series to obtain the proper ratio between the steam speed and the blade speed, for high efficiency. At high power and high revolutions some of the stages or rows of blades are arranged to operate in parallel. In this way the number of stages or rows of 45 blades operating in series is reduced and the ratio between the steam speed and the blade speed necessary for high efficiency is maintained.

By dividing the turbine into groups of 50 stages or rows of blades and properly proportioning the flow of steam through these stages or rows of blades I am able to secure a desired division of power.

In carrying out my invention I may provide a turbine comprising high pressure 55 stages or rows of blades divided into two groups 1 and 2 and low pressure stages or rows of blades, group 3. The group 1 is provided with a steam inlet 4 and a pipe 5 by means of which steam after passing 60 through all of the stages or rows of blades of this group will be directed to the steam chest 6 of the high pressure group 2. The exhaust end of the group 2 is provided with a pipe 7 which communicates with the inlet of 65 the low pressure group 3. Live steam may be admitted to the group 2 through an inlet pipe 8. The exhaust end of the group 1 is connected to the inlet of the low pressure group 3 by means of a pipe 9. A pipe 10 70 offers communication between the shells of the groups 1 and 2 back of the first stages or rows of blades in each group so that part of the steam which passes through the first stages of one group may be made to pass 75 over to the other group and to unite with the steam which has passed through the first stages of this group.

The low pressure group 3 is mounted on a propeller shaft 11 and delivers its power directly to such shaft and the shafts 12 and 13 of the high pressure groups 1 and 2 respectively are arranged to drive the shaft 11 through a speed reduction gear 14. The low pressure group 3 is provided with an exhaust 85 15 which communicates with a condenser (not shown).

The pipes 5, 9 and 10 respectively have valves 18, 20 and 19.

In the embodiment of the invention shown 90 in Fig. 1 the inlet 8 is closed at reduced power and all of the steam is admitted to group 1 through the inlet 4 and flows in series through all the stages or rows of blades in this group, then through the pipe 95 5 to the chest 6 of group 2, flows in series through all the stages or rows of blades in this group, then through the pipe 7 to the low pressure group 3 and thence to the exhaust 15.

At high power the steam is divided. A large proportion, say three fourths, for example, is admitted to group 1 through the inlet 4 and the remaining one-fourth of the flow is admitted to group 2 through the inlet 8. The steam thus divided flows through

the first stages or rows of blades of the two groups in parallel. The larger volume of steam after passing through the first stages or rows of blades in the group 1 subdivides and two-thirds of this steam, equal to one-half of the total steam, flows through the pipe 10 to group 2 and unites with the smaller volume which has passed through the first stages or rows of blades in this group. The steam then flows through the remaining stages or rows of blades of the two groups still in parallel one-fourth of the total steam now flowing through group 1 and three-fourths through group 2. The steam then flows through the pipes 9 and 7 to the low pressure part 3 of the turbine and thence to the exhaust 15.

When operating with the steam flowing in series through the groups 1 and 2, the inlet 8 will be closed, the pipe 10 will be closed by means of the valve 19, the pipe 9 will be closed by the valve 20, and the valve 18 will be opened.

When operating with the steam flowing in parallel through the groups 1 and 2, the inlet 8 will be opened, the valve 18 will be closed and the valves 19 and 20 opened.

From the foregoing description it is apparent that at reduced power all of the steam flows in series through all of the stages or rows of blades in the two high pressure groups, and at high power the steam flows in parallel through the stages of these two groups and the number of stages operating in series is materially reduced. By properly proportioning the division of the flow admitted to each group and the division of the flow passing through the later stages or rows of blades these groups may be made to deliver equal powers.

In the embodiment of the invention shown in Fig. 2, the propeller shaft 11 is provided with a clutch 16 between the reduction gearing 14 and the main turbine 3, the turbine 3 has a live steam inlet 17 provided with a valve 22 and the pipe 7 between the group 2 and the main turbine 3 has a valve 21.

In this embodiment of the invention the turbine composed of the groups 1 and 2 is what is commonly known as the cruising turbine.

The cruising turbine comprises a plurality of stages or rows of blades divided into two groups on separate shafts. At high power, that is, high cruising speeds, the steam flows through these two groups in parallel divided and proportioned in the same manner as in the high pressure groups 1 and 2, Fig. 1 hereinbefore described. At reduced cruising speeds and reduced power, all the steam flows in series through all the stages or rows of blades of these groups in the same manner as in high pressure groups 1 and 2, Fig. 1 hereinbefore described. The group 3 is the low pressure element of the

turbine at all cruising speeds and receives the exhaust steam from group 2 of the cruising turbine at the low cruising speeds and from both group 1 and group 2 at the high cruising speeds.

At speeds higher than the cruising speeds the cruising turbine is disconnected by means of the clutch 16 and the propeller shaft is driven by the group 3 alone, live steam being admitted thereto through the pipe 17 controlled by the valve 22, the valves 20 and 21 being closed.

In the embodiment of the invention illustrated in Fig. 3, the turbine is composed of two high pressure groups 1 and 2 of stages or rows of blades arranged on shafts 12 and 13 respectively and two low pressure groups 3^a and 3^b of stages or rows of blades mounted on separate shafts 23 and 24 respectively. The shafts 12, 13, 23 and 24 are arranged to drive the propeller shaft 11 through a reduction gear 14^a.

The exhaust end of the group 2 is provided with a pipe 7^a which communicates with the inlet of the low pressure groups 3^a and 3^b. The exhaust end of the group 1 is connected by a pipe 9^a having a valve 20^a with the inlet of the low pressure groups. The pipes 7^a and 9^a are connected to a manifold in which the steam is divided and an equal amount delivered to each low pressure group.

The low pressure stages or rows of blades are divided into two double flow groups in which the inlet is at the center and the steam flows in both directions to the exhausts 15^a at the ends of each group.

The operation of the embodiment of the invention illustrated in Fig. 3 is the same as that shown in Fig. 1 with the exception that after the steam passes through the groups 1 and 2 it is divided and one-half of the flow passes through each of the groups 3^a and 3^b of the low pressure stages or rows of blades.

In the foregoing specification, and following claims I use the term "steam." I use this term as a convenient means for describing an elastic fluid of any kind, suitable for driving a turbine.

Any form of transmission may be employed, the mechanical gearing shown being solely for purpose of illustration, and if desired the gearing may be dispensed with and power taken directly off the shafts 12 and 13.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having thus described my invention what I now claim as new and desire to secure by Letters Patent, is:

1. A steam turbine comprising a plurality of stages or rows of blades arranged in groups, means whereby, at reduced power, all of the steam will flow in series through all of the stages or rows of blades of these groups, means whereby, at high power, part 10 of the steam will be admitted to each group and flow in parallel through the first stages or rows of blades, and means whereby the steam will be subdivided and flow, still in parallel but in changed proportions through 15 the remaining stages or rows of blades of these groups.

2. A steam turbine comprising a plurality of stages or rows of blades arranged in groups on separate shafts, means whereby, 20 at reduced power, all of the steam will be caused to flow in series through all of the stages or rows of blades of these groups, means whereby, at high power, part of the steam will be admitted to each group and 25 caused to flow in parallel through the first stages or rows of blades, and means whereby the steam will be subdivided and caused to flow, still in parallel, but in changed proportion through the remaining stages or 30 rows of blades of these groups whereby a desired division of power between the shafts may be maintained.

3. A steam turbine comprising high pressure and low pressure stages or rows of 35 blades, with the high pressure stages arranged in groups, means whereby, at reduced power, all of the steam will be caused to flow in series through all of the high pressure stages or rows of blades of these 40 groups and then through the low pressure stages of the groups to the exhaust, means whereby at high power part of the steam will be admitted to each group of high pressure stages or rows of blades and caused 45 to flow in parallel through the first stages or rows of blades, and means whereby the steam will be subdivided and caused to flow, still in parallel but in changed proportions, through the remaining high pressure stages 50 or rows of blades then through the low pressure stages or rows of blades of these groups to the exhaust.

4. A steam turbine comprising high pressure and low pressure stages or rows of 55 blades with the high pressure stages arranged in groups on separate shafts, means whereby at reduced power all of the steam flows in series through all of the high pressure stages or rows of blades of these groups 60 then through the low pressure stages or rows of blades of the groups to the exhaust, means whereby at high power the steam, part being admitted to each group of high pressure stages or rows of blades, flows in 65 parallel through the first stages or rows of

blades, subdivides and flows still in parallel but in changed proportions through the remaining high pressure stages or rows of blades of the groups, whereby a desired division of power between the shafts may be maintained, and means for passing the steam through the low pressure stages or rows of blades to the exhaust. 70

5. A steam turbine comprising a plurality of stages or rows of blades arranged in two groups on separate shafts, means for admitting the initial steam to one of the groups at reduced power, means for carrying the steam from the exhaust end of the first group to the inlet of the second group, 75 means for exhausting the steam from the second group, whereby all the steam flows in series through all the stages or rows of blades of the groups, means for admitting the initial steam to both groups at high 80 power, means for subdividing the steam after it has passed the first stages or rows of blades, means for exhausting the steam from both groups, whereby the steam flows in parallel through the first stages or rows 85 of blades of the groups, subdivides and flows still in parallel but in changed proportions through the remaining stages or rows of blades of these groups whereby a desired division of power between the shafts 90 may be maintained. 95

6. A steam turbine comprising high pressure and low pressure stages or rows of blades with the high pressure stages or rows arranged in two groups, means for admitting the initial steam to one of the groups at reduced power, means for carrying the steam from the exhaust end of the first group to the inlet of the second group, means for carrying the steam from the exhaust end of the 100 second group to the inlet of the low pressure stages or rows of blades, whereby all the steam flows in series through all the stages or rows of blades of the high pressure groups then through the low pressure stages 105 or rows of blades to the exhaust, means for admitting the initial steam to both groups at high power, means for subdividing the steam after it has passed the first stages or rows of blades, means for carrying the steam from the exhaust end of each group to the inlet of the low pressure stages or rows of blades, whereby the steam flows in parallel through the first stages or rows of blades of the two 110 groups, subdivides and flows still in parallel but in changed proportion through the remaining stages or rows of blades of the high pressure groups, then through the low pressure stages or rows of blades to the exhaust. 115

7. A steam turbine comprising high pressure and low pressure stages or rows of blades with the high pressure stages or rows arranged in two groups on separate shafts, means for admitting the initial steam to one 120 of the groups at reduced power, means for 125

carrying the steam from the exhaust end of the first group to the inlet of the second group, means for carrying the steam from the exhaust end of the second group to the 5 inlet of the low pressure stages or rows of blades, whereby all the steam flows in series through all the stages or rows of blades of the high pressure groups then through the low pressure stages or rows of blades to 10 the exhaust, means for admitting the initial steam to both groups at high power, means for subdividing the steam after it has passed the first stages or rows of blades, means for carrying the steam from the exhaust end of 15 each group to the inlet of the low pressure stages or rows of blades, whereby the steam flows in parallel through the first stages or rows of blades of the two groups, subdivides and flows still in parallel but in changed 20 proportions through the remaining stages or rows of blades of the high pressure groups, whereby a desired division of power between the shafts may be maintained, then through the low pressure stages or rows of blades to 25 the exhaust.

8. A steam turbine comprising high pressure stages or rows of blades and double flow low pressure stages or rows of blades with the high pressure stages or rows arranged in 30 two groups on separate shafts, the low pressure stages or rows of blades being arranged in two groups on separate shafts, means for admitting the initial steam to one of the

high pressure groups at reduced power, means for carrying the steam from the exhaust end of the first group to the inlet of the second group, means for carrying the steam from the exhaust end of the second group to the inlet of the low pressure stages or rows of blades, whereby all the steam flows in series through all the stages or rows of blades of the high pressure groups then through the low pressure stages or rows of blades to the exhaust, means for admitting the initial steam to both high pressure groups 45 at high power, means for subdividing the steam after it has passed the first stages or rows of blades, means for carrying the steam from the exhaust end of each group to the inlet of the low pressure stages or rows of blades, whereby the steam flows in parallel through the first stages or rows of blades of the two groups, subdivides and flows still in parallel but in changed proportions through the remaining stages or rows 50 of blades of the high pressure groups, whereby a desired division of power between the shafts may be maintained, then through the low pressure stages or rows of blades to the exhaust. 60

This specification signed and witnessed this seventh day of March, 1917.
